13,153-

Aug 8, 1882.

UNITED STATES PATENT OFFICE.

EDUARD LEISSNER, OF NEW YORK, N. Y.

DESIGN FOR WALL-PAPER.

SPECIFICATION forming part of Design No. 13,153, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A consists of a cluster of five flower-like figures, resembling dandelions. G is a cluster of four such flowers; H, a cluster of three; B, a cluster of four in the form of a pyramid. b is a cluster of two such flowers, and a represents one of such flowers. I represents a vine bearing leaves triangular in shape, running over the background and filling the spaces between the flower figures already described. The whole effect of the design is that of a thickly-

leaved vine, upon which grow the flower figures described. 25

I claim—

1. The design for wall-paper, consisting of the figure A, substantially as shown.
2. The design for wall-paper, consisting of the figure H, substantially as shown. 30
3. The design for wall-paper, consisting of the figure G, substantially as shown.
4. The design for wall-paper, consisting of the figure B, substantially as shown.
5. The design for wall-paper, consisting of the figure b, substantially as shown. 35
6. The design for wall-paper, consisting of the vine I, substantially as shown.
7. The design for wall-paper, consisting of the figures A B G H, a b and vine I, substantially as shown. 40

EDUARD LEISSNER.
